Primary Examiner — Zenia I Bennett(74) *Attorney, Agent, or Firm* — Li & Cai Intellectual Property (USA) Office(57) **CLAIM**

The ornamental design for a folding laser comb, as shown and described.

DESCRIPTION

FIG. 1 is a front, right side and top perspective view of a folding laser comb showing the claimed design in a closed position;

FIG. 2 is a front elevational view thereof in a closed position;

FIG. 3 is a rear elevational view thereof in a closed position;

FIG. 4 is a left side elevational view thereof in a closed position;

FIG. 5 is a right side elevational view thereof in a closed position;

FIG. 6 is a top plan view thereof in a closed position;

FIG. 7 is a bottom plan view thereof in a closed position;

FIG. 8 is a front and right side perspective view thereof in a half-open position; and,

FIG. 9 is a rear and right side perspective view thereof in an open position.

The dashed broken lines in the drawing depict portions of the folding laser comb that form no part of the claimed design.
